US00D972618S

(12) **United States Design Patent** (10) **Patent No.:** **US D972,618 S**
(45) **Date of Patent:** **** Dec. 13, 2022**

(54) **NETWORK CAMERA**

(71) Applicant: **SHENZHEN ANYUANWEI TECHNOLOGY CO., LTD**, Shenzhen (CN)

(72) Inventor: **Wenjun Li**, Shenzhen (CN)

(73) Assignee: **SHENZHEN ANYUANWEI TECHNOLOGY CO., LTD**, Shenzhen (CN)

(**) Term: **15 Years**

(21) Appl. No.: **29/769,030**

(22) Filed: **Feb. 3, 2021**

(51) LOC (13) Cl. **16-01**

(52) U.S. Cl.

USPC **D16/203**

(57) **CLAIM**

The ornamental design for a network camera, as shown and described.

DESCRIPTION

FIG. 1 is a perspective view of a network camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the network camera and form no part of the claimed design.

1 Claim, 7 Drawing Sheets
